UNITED STATES PATENT OFFICE.

FREDERICK H. GIBBS, OF BROOKLYN, NEW YORK, ASSIGNEE TO AMERICAN CAR AND FOUNDRY COMPANY, OF NEW YORK, N. Y., A CORPORATION OF NEW JERSEY.

MINE-CAR WHEEL AND AXLE.

1,256,484.

Specification of Letters Patent. Patented Feb. 12, 1918.

Application filed November 22, 1916. Serial No. 132,827.

To all whom it may concern:

Be it known that I, FREDERICK H. GRASS, residing at borough of Brooklyn, county of Kings, city and State of New York, and being a citizen of the United States, have invented certain new and useful Improvements in Mine-Car Wheels and Axles, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a central vertical longitudinal sectional view through a wheel, axle and journal box in assembled position;

Fig. 2 is an end elevational view of the 25 wheel hub;

Fig. 3 is a vertical sectional view through the wheel hub, the section being taken on line 3—3 of Fig. 1 and showing in dot and dash line the bearing rollers in position;

30 Fig. 3^a is a view taken on the same section line showing but one of the bearing rollers in position in dot and dash lines;

Fig. 4 is a view similar to Figs. 3 and 3^a but taken on line 4—4 of Fig. 1 looking in 35 the direction indicated by the arrow and with the bearing rollers removed;

Fig. 5 is a sectional view, the section being taken approximately on the line 4—4 of Fig. 1 showing fragments of a mine car in elevation;

Fig. 6 is a vertical sectional view, the section being taken on line 6—6 of Fig. 5;

Fig. 7 is a detached view of the annulus hereinafter referred to; and

45 Fig. 8 is a slightly modified detail arrangement showing a bearing plug inserted in the outer end of the tubular axle.

The object of the invention is to provide a roller bearing mine car wheel formed as 50 an integral casting adapted to retain therein

bearing rollers and to hold said bearing rollers in position while the wheel is mounted on an axle and primarily without the aid of extraneous devices. Incidental to such an arrangement, auxiliary movable devices 55 are provided for purposes hereinafter set forth.

Another object of the invention is to provide a tubular axle especially adapted to co-operate with the wheel herein illustrated and described, which wheel is reinforced within the portion thereof subjected to the greatest stresses, the reinforcement forming, within the outer end portions of the axle, lubricant-pockets adapted to receive fluid-lubricant 65 for well understood purposes.

Another feature of the invention is a simple and easily manipulated latching device adapted to secure the wheel in position upon the axle and preferably in fixed relation to 70 the journal box.

Referring specifically to the parts, 10 is a tread, 11 a flange, 12 the spokes and 13 the hub portions of a mine car wheel which is preferably of the roller bearing type and 75 is provided with a closed hub portion 14 comprising a wall of metal in alignment with the tubular axle 15 upon which the wheel is adapted to rotate.

Cast integrally with the tread, spokes and hub are roller bearing flanges 16 and 17, the former of which is continuous and the latter of which is discontinuous or intermittent in alignment with an opening formed in the outer hub portion, which opening is shown in Figs. 1 and 2 as closed by an insertable screw-threaded plug 18, which plug 18 is provided with a flanged head portion 19 adapted to serve as a stop to prevent excessive inward thrust of said plug when it is being inserted in position.

Within the finished wheel there is provided a bearing sleeve 20 which may be cast in position during the process of casting the hub, spokes, flanges, etc., or said sleeve may 95 be inserted through the axle opening 21 in the hub after the wheel has been cleaned and its inner surface bored, as is common in the art.

As the flange 17 is intermittent in alignment

ment with the opening adapted to be closed by the plug 18, it is evident that the bearing rollers 22 may be inserted within the hub while the wheel is in position upon its axle 5 or before the wheel is so positioned.

To assist in retaining the rollers 22 in position when the wheel is removed from the axle, a compressible annulus 23 is provided which, as shown in Fig. 7, is of spring metal 10 and is adapted to be compressed into a smaller diameter. The annulus 23 extends outwardly so as to project into the path of travel of the rollers when they are being projected through the outer face of the hub 15 into said hub, and to remove said annulus from said path all that is necessary is to force the wedge-shaped end portion 22a of the roller into contact with said annulus 23, whereupon the diameter of the annulus will 20 be reduced and the rollers may pass, one at a time, through the opening from which the plug 18 shall have been removed. Said opening A is shown in Figs. 3 and 3a as occupied by a roller 22, and it is to be noted 25 that the opening A is eccentrically disposed with relation to the axle opening of the hub, and preferably the center of the opening A is in alignment with the channels B, B which receive the conical end portions of the rollers 22.

An advantage in forming the flanges 16 and 17 integrally with the hub is that they may be finished in one operation when a properly formed core is used when casting a 25 wheel and there is no possibility of the flanges being improperly disposed with relation to the conical end portions of the rollers so as to produce undue binding of the rollers within the hub, or undue looseness 40 of adjustment of parts, which is always possible where the supporting flanges for the rollers are formed separately from the hub. When it is desired to remove the rollers from the wheel, the wheel is preferably re- 45 moved from the axle and rotated so that the plug 18 is at the lower side, whereupon said plug may be removed, and a slight pressure upon the inner ends of the rollers 22, one at a time, will project said rollers through the 50 opening A so that they may be removed from the wheel hub.

Various types of lubricant are employed with roller bearing mine car wheels, but to permit the use of fluid-lubricant, where desired, I prefer to employ within the outer 55 end of the axle 15, a lubricant pocket 30 which pocket serves as a reinforce for the outer end portion of the axle and to provide maximum storing capacity for lubricant as 60 well as to strengthen that portion of the axle subjected to the greatest stresses, said tubular lubricant pocket preferably extends, as shown in Fig. 1, within the zone of the journal box 31. The fluid lubricant may be

permitted to flow through the open end portion 32 of the axle, if desired, or lubricant ducts 33 may be provided through the shell of the reinforcement 30 and the shell of the axle 15.

Where fluid-lubricant is not employed, it 70 is obvious that the plug 18 may be removed and lubricant injected through the opening A in sufficient quantity to properly lubricate the rollers 22 which require much less lubricant than is required in the type of 75 wheels where roller bearings are not employed.

Should it be desired to receive the thrust of the wheel hub directly on the end of the axle, a plug 25 may be inserted in the opening 80 32, as shown in Fig. 8, said plug being represented as formed from a commercial rivet which may be of hardened steel and polished, if desired.

The journal box 31 is of the conventional 85 type in its general arrangement and the general features of construction of these boxes are common in the art, but I have added attaching flanges 40 and 41, to the latter of which is preferably permanently attached a 90 gravity latch 42 which is adapted to co-operate with a flange portion 43 of said journal box and with the annular flange 44 formed on the inner end of the hub 13 of the wheel, said latch comprising a U-shaped bottom 95 portion 45 having a vertical wall 46 which lies within the flange 43 of the journal box and a vertical flange 47 which lies outside of the annular flange 44 of the wheel hub and between said flange and the spokes 12 100 of the wheel when the parts are assembled, as shown in Fig. 1.

To secure said gravity latch 42 in position, it is preferably connected with said flange 41 of the journal box by a through 105 bolt 50, upon which said latch may swing downwardly by gravity to release the wheel when desired, but in its normal elevated position said latch 42 is locked by means of a cotter pin 51 passing through the extension 52 of said latch and the flange 40 of the journal box. It is obvious that when the latch is in its elevated position the wheel 110 is locked in position upon the axle and in fixed relation to the journal box, but to prevent excessive wear between the inner end 115 of the hub of the wheel and the outer face of the journal box, a washer, as 55, is interposed.

It is obvious that while the invention is 120 shown applied to a mine car wheel and journal box assembly which is attached to a truck or car body indicated generally by the reference character C, that said wheel may be employed in other relations and for 125 other purposes without departing from the spirit of the invention, as set forth in the following claims.

What I claim is:

1. In combination, a pedestal box, a cast mine car wheel comprising a flanged tread, spokes and a hub provided with a plurality of annular channels, cylindrical bearing rollers with end portions in said channels, the flange of one of said channels being intermittent to permit insertion of said rollers into said hub, roller-retaining means held in the hub in proximity to the break in said flange, an axle projecting from said pedestal box and means locking the wheel thereon thereby positioning said axle to project through said retaining means.
2. In combination, a pedestal box, a cast mine car wheel comprising a flanged tread, spokes and a hub provided with a plurality of annular channels, bearing rollers with end portions entering said channels, a flange of one of said channels being intermittent to permit insertion of said rollers into said hub, a resilient roller-retaining means in the hub in proximity to the break in said flange, an axle, and means locking the wheel thereon thereby positioning said axle to project into said pedestal box, and through said roller-retaining means.
3. In combination, a pedestal box, a cast mine car wheel comprising a flanged tread, spokes and a hub provided with a plurality of annular channels, there being a roller-receiving opening through one of said channels, a removable closure for said opening, an axle, means locking this wheel thereon thereby positioning said axle to extend into said pedestal box and hub, bearing rollers insertible through said opening to travel about said axle with their ends in said channels, and an auxiliary roller-retaining means held in movably interlocked position within said hub.
4. In combination in a mine car, a pedestal box, a tubular axle, a tubular reinforcement forming a lubricant reservoir within an end portion of the axle, a roller bearing wheel rotatable independently of and on said axle with its rollers in vertical alignment with said reinforcement and means engaging the pedestal box and the wheel for locking said wheel rotatably on said axle in fixed relation to said pedestal box and maintaining the rollers in predetermined lubricant-receiving relation to the lubricant reservoir.
5. In combination in a mine car, a pedestal box, a tubular axle extending therebeyond at one end, a tubular reinforcement forming a lubricant reservoir within said end portion of the axle and extending within the zone of the pedestal box, a roller bearing wheel rotatable on and independently of said axle with its rollers in vertical alignment with said reinforcement and means locking said wheel rotatably on said axle
- causing said wheel to assist in preserving 65 the relation of said reinforcement and pedestal box.
6. As an article of manufacture, a mine car wheel comprising a flanged tread, spokes, a closed hub end and a portion 70 adapted to cooperate with means for attaching said wheel on an axle adapted to extend into said hub, said hub having a continuous roller-supporting flange within the inner end of the hub and a discontinuous 75 roller-supporting flange within the outer end of the hub, all cast as an integer.
7. In combination, a cast mine car wheel comprising a tread, spokes and a hub having an axle opening and a hub portion 80 closed in alignment therewith and provided with an eccentrically disposed roller-receiving opening in its outer face, cylindrical rollers insertible through the latter opening into a roller-retaining chamber in said hub, 85 a pedestal box, an axle and means connecting said pedestal box, wheel, axle and rollers in predetermined relation.
8. In combination, a pedestal box, a tubular axle therein extending beyond said pedestal box, a reinforce tube within the extended end portion of said axle, said reinforce tube extending within the zone of said pedestal box, a roller-bearing-wheel having rollers bearing on the axle within the zone 95 of said reinforce tube, and means attaching said wheel to said journal box and maintaining said reinforce tube in proper relation to each.
9. In combination, a journal box, a swing-latch pivotally supported thereby and adapted to drop therefrom by gravity and a wheel having an inner hub-flange adapted to be engaged by said latch when in its raised position.
10. In combination, a roller bearing mine car wheel comprising a tread and hub formed integrally with a roller-supporting flange within an inner portion of the hub, a contractible annulus within an outer portion of the hub, cylindrical rollers retained by said flange and annulus, a pedestal, an axle and wheel attaching means correlating said pedestal and hub and said annulus and said axle.
11. In combination, a tubular axle, a combined lubricant receptacle and tubular reinforcement within an end portion thereof, a wheel rotatable on and independently of the reinforced portion of said axle and 110 housing the entrance to the lubricant receptacle, and means adapted to removably attach said wheel on said axle.
12. In combination, a pedestal, an axle projecting therefrom, a cast mine car wheel 125 comprising a flanged tread, spokes and a hub provided with a plurality of annular channels, cylindrical bearing rollers with

end portions in said channels, a flange of one of said channels being intermitted to permit insertion of said rollers into said hub, roller-retaining means held in proximity to the break in said flange, and means locking said wheel on said axle with an end of the latter circumscribed by said retaining means.

13. In combination in a mine car, a pedestal box having a journal bearing portion, a tubular axle extending through and out-

wardly beyond said bearing portion, a tubular reinforce within the outer end portion of said axle, a roller bearing wheel wholly enclosing the end portion of said axle and cylindrical bearing rollers in said wheel normally in vertical alinement with said tubular reinforce.

In witness whereof I have hereunto set my hand.

FREDERICK H. GIBBS.
